FIG. 5

FIG. 8

FIG. 7

FIG. 1 is a perspective view of the gun case showing my new design as seen from above the left front end thereof and with its lid in open position;

FIG. 2 is a perspective view of the gun case as seen from above the right front end thereof and with the lid in fully closed position;

FIG. 3 is a front elevational view of the gun case;

FIG. 4 is an elevational view of the left-hand end of the gun case;

FIG. 5 is a rear elevational view of the gun case;

FIG. 6 is a bottom plan view of the gun case;

FIG. 7 is a cross-sectional view of the gun case taken along lines 7-7 of FIG. 3;

FIG. 8 is a cross-sectional view taken along lines 8-8 of FIG. 3.

The characteristic features of my design reside in the specific configuration of the interior of the case.

I claim:

The ornamental design for a gun case, substantially as shown and as described.
